APRON TUYÈRE FOR STOKERS

Royce L. Beers, Birmingham, Mich., assignor to
 Detroit Stoker Company, Monroe, Mich., a cor-
 poration of Michigan

Application October 7, 1935, Serial No. 43,949

13 Claims. (Cl. 110—75)

This invention relates to stoker constructions of the sprinkler type in which mixed fine and coarse fuel is thrown into the furnace chamber over the grate. With this type of construction, 5 there is a tendency for the fine fuel, and particularly the dust, to drop down adjacent to the front wall of the furnace where it will accumulate without being fully burned. To avoid such an effect furnaces have been provided with apron 10 tuyères which project rearward and incline downward from the front wall and have air discharge openings at the rear end thereof. With such a construction, the fine fuel and dust falling upon the inclined apron will travel down the same, 15 meeting the air at the lower rear end, and being blown rearward therefrom.

The present invention relates to apron tuyères of the type just described and has for its object the obtaining of a construction formed in units 20 which can be easily installed and quickly removed at any time for repair or replacement.

It is a further object to provide effective means for protecting the tuyère from the furnace heat so as to prevent burning out of the same.

With these objects in view, the invention consists in the construction as hereinafter set forth in the drawings:

Figure 1 is a vertical section through a portion 30 of the front wall of the furnace below the fuel feed opening therein showing my improved open tuyère applied thereto;

Figure 2 is an elevation viewed from the right of Figure 1 showing the manner of mounting and securing a series of tuyères across the furnace chamber;

Figure 3 is a perspective view of one of the tuyère sections removed;

Figure 4 is a similar view showing the heat insulating unit for the tuyère.

As shown in Figure 1, the furnace has a front wall A with a fuel opening B therein, in front of which is the stoking and sprinkling mechanism (not shown). C is a replaceable wear member which forms the bottom of the fuel opening and which has a hooked engagement with a member D on the furnace wall. E is a member secured adjacent to the inner face of the furnace wall and provided with an upwardly extending hook F for supporting the apron tuyère members. The 45 members E and F extend completely across the furnace chamber to the side walls G and G¹ thereof.

The apron tuyère units are of the construction shown in Figure 3, being provided with a downwardly and rearwardly inclined apron portion H

and a downwardly and forwardly inclined return-portion I. The portion H is provided on its underside with a hook J for engaging the hook F and thereby retaining the unit upon the furnace wall. The hook J is in the central portion of the 5 apron H and merges into a rib J¹ extending downwardly on the inner side of said apron. On opposite sides of the lower portion of this rib are the wings J² and J³ which extend for the full width of the apron H, and forming between the 10 same and the apron air channels J⁴ with outwardly opening ports J⁵ near the bottom of the apron. The portion I is of a channel-shaped cross section having the downwardly extending sides I¹ and the inwardly extending flanges I². 15 This channel is open at the inner end and inclines downward towards the forward end which is closed by the portion I³ bearing against the member E. Thus, when the unit is mounted with its hook J engaging the hook F, it will form in 20 connection with the member E, a triangular shaped member.

In installing these tuyère units, they are successively placed in position with the hooks J engaging the member F which forms a rail extending completely across the front wall of the furnace chamber. The units can then be slid upon this rail into proper position with the adjacent units abutting against each other. To form a better seal between these units the opposite edges 25 of the apron H are fashioned to form a break joint, being provided on one edge with the projecting tongue portion H¹ and upon the opposite edge with a groove or rabbet H² for engaging the tongue of the adjacent unit. These tongues and 30 grooves are engaged by laterally sliding the unit upon the rail F. However, at the ends of the series it is necessary to provide closing members for forming tight joints with the side walls G and G¹. This is accomplished by a member K which 35 is similar in form to the apron unit but of lesser width. On one side of this unit is a groove K¹ corresponding to the grooves H² and adapted to receive the tongue H¹ of the adjacent unit, while the opposite side of the member K is plain to bear against the furnace wall. Thus, in installing the units one member K is first placed adjacent to one wall of the furnace chamber, the apron units are then successively installed and slid laterally to engage the tongues H¹ with the grooves 40 H², and finally at the opposite ends of the series a second member K is inserted. This is arranged with its plain side against the tongue side of the adjacent unit and its grooved side against the furnace wall, thus requiring no lateral movement 45 50 55

and completely filling the space between the last unit and the wall. A lug J^6 projects from one side of each unit and engages a corresponding recess at the opposite side of the adjacent unit.

5 Air is supplied to the chamber within the units through a suitable conduit (not shown) at one or both ends of the series. From the chamber, air passes outward through the channels J^4 and ports J^5 blowing the dust and fine fuel rearwardly and assisting in supporting combustion. This constant discharge of air will keep the apron portion of the tuyère sufficiently cool, but the lower portion I requires protection against the intense furnace heat. This is accomplished by providing a series of heat insulating units L , preferably formed of firebrick, and so fashioned as to slidably engage the channel portions I and to completely protect the same. As shown in Figure 4, the member L has 20 a lower portion L^1 which is of the full width of the member I and an upper portion L^2 of less width which fits within the channel and has the under-cut grooves L^3 for engaging the flanges I^2 . This permits of slidably engaging 25 the members L with the apron units after the latter have been mounted in position within the furnace chamber. When thus installed, the units L will abut against each other, each having a front portion L^4 for covering the rear ends of 30 the members I , while the portion L^1 extends beneath the member I and protects the same.

My improved apron tuyère constructed as above described, is particularly adapted for quick installation in the furnace and also for 35 the replacement of any unit which may have become damaged. The forming of the heat protecting units L as separate and distinct from the tuyère units is advantageous, as these may become damaged and without any injury to the 40 tuyère and can be easily replaced. Also, by forming these protecting units of material such as firebrick they can be made of greater thickness and have greater inherent strength than any insulation formed from plastic material applied directly to the metal. To further protect the units, air channels are formed adjacent to the engaging 45 portions of the metal and of the insulating member, these being connected to the air supply through a port I^4 formed in the member I . This permits a flow of air through said port around 50 the clearance space between the portion L^2 and the channel member I , and particularly along the grooves L^3 adjacent to the flanges I^2 . As a consequence, the metal is held at a sufficiently 55 low temperature to retain its rigidity and to prevent burning out.

Another advantageous feature is the break joint engagement between the successive tuyère units. This not only prevents escape of air where 60 it is not desired, but also prevents the dust from the fuel passing through the crevice and filling up the tuyère.

What I claim as my invention is:

1. In a furnace, the combination with a furnace wall, of an apron tuyère detachably engaging said wall and projecting into the furnace chamber, said unit comprising an apron portion extending rearward and downward from said wall, a return-portion extending forward to said 70 wall and together therewith and said apron portion forming an air chamber with ports opening therefrom through the lower end of said apron, and a heat insulating unit detachably engaging said return-portion and covering the same.

2. In a furnace, the combination with a furnace wall, of an apron tuyère detachably engaging said wall and projecting into the furnace chamber, said unit comprising an apron portion extending rearward and downward from said wall, a return-portion extending forward to said 5 wall and together therewith and said apron portion forming an air chamber with ports opening therefrom through the lower end of said apron, and a heat insulating unit slidably engaging said return-portion from the rear end thereof and covering the rear end and bottom thereof.

3. In a furnace, the combination with a furnace wall, of an apron tuyère detachably engaging said wall and projecting into the furnace chamber, said unit comprising an apron portion extending rearward and downward from said wall, a return-portion extending forward and inclining downward to said wall forming in connection therewith and said apron an air chamber having ports opening through the lower end of said apron, and a heat insulating unit slidably engaging said return-portion from the rear end thereof and covering said rear end and bottom 20 25 whereby said insulating unit will be held in position by gravity.

4. In a furnace, the combination with a furnace wall, of an apron tuyère detachably engaging said wall and projecting into the furnace chamber, said unit comprising an apron portion extending rearward and downward from said wall, a return-portion extending forward and inclining downward to said wall being of a channel-shaped cross section open at the rear end, and a 30 35 heat insulating unit having a portion slidably engaging said channel and having portions covering the rear end and bottom thereof.

5. In a furnace, the combination with a furnace wall, of an apron tuyère detachably engaging said wall and projecting into the furnace chamber, said unit comprising an apron portion extending rearward and downward from said wall, a return-portion extending forward to said wall and together therewith and said apron portion forming an air chamber with ports opening therefrom through the lower end of said apron, a heat insulating unit detachably engaging said return-portion and covering the same, and means for flowing air from said chamber 40 45 adjacent to the engaging portions of said return-portion and heat insulating unit to lower the temperature thereof.

6. In a furnace, the combination with a furnace wall, of an apron tuyère detachably engaging said wall and projecting into the furnace chamber, said unit comprising an apron portion extending rearward and downward from said wall, a return-portion extending forward and inclining downward to said wall being of a channel-shaped cross section open at the rear end, a heat insulating unit having a portion slidably engaging said channel and having portions covering the rear end and bottom thereof, and means for feeding air from said chamber through 50 55 said channel to lower the temperature of the metal in engagement with said heat insulating unit.

7. In a furnace, the combination with a furnace wall, of an apron tuyère detachably engaging said wall and projecting into the furnace chamber, said tuyère being formed of a series of units, each having an apron portion inclining rearward and downward from said wall, a return-portion extending forward to said wall and 70 75

together therewith and said apron portion forming an air chamber with ports opening through the lower end of said apron portion, said units having their edges fashioned to form a break joint therebetween.

5. 8. In a furnace, the combination with a furnace wall, of an apron tuyère detachably engaging said wall and projecting into the furnace chamber, said tuyère being formed of a series of units, each having an apron portion inclining rearward and downward from said wall, a return-portion extending forward to said wall and together therewith and said apron portion forming an air chamber with ports opening through 10 the lower end of said apron portion, the apron portions of said units being formed with a projecting tongue on one side and a groove on the opposite side whereby one unit may be moved laterally into engagement with an adjacent unit 15 to form a break joint therebetween.

9. In a furnace, the combination with a furnace wall, of an apron tuyère detachably engaging said wall and projecting into the furnace chamber, said tuyère being formed of a series of 20 units, each having an apron portion inclining rearward and downward from said wall, a return-portion extending forward to said wall and together therewith and said apron portion forming an air chamber with ports opening through 25 the lower end of said apron portion, the apron portions of said units being formed with a projecting tongue on one side and a groove on the opposite side whereby one unit may be moved laterally into engagement with an adjacent unit 30 to form a break joint therebetween, and a filler at the end of the series for closing the gap between the last unit and the furnace side wall.

10. An apron tuyère unit for attachment to 35 furnace walls comprising an apron portion inclining rearward and downward from the wall, a rib arranged centrally on the underside of said apron portion for reinforcing the same, wings projecting laterally from the opposite sides of the rearward portion of said rib and extending beneath the end of the apron portion to leave open 40 ports therebetween, a hook at the upper forward end of said apron portion for attachment to the furnace wall, and a portion inclining downward and forward from the rear end of said wings to 45

said furnace wall and forming in connection therewith and said apron an air chamber.

11. An apron tuyère unit for attachment to furnace walls comprising an apron portion inclining rearward and downward from the wall, a 5 rib arranged centrally on the underside of said apron portion for reinforcing the same, wings projecting laterally from the opposite sides of the rearward portion of said rib and extending beneath the end of the apron portion to leave open 10 ports therebetween, a hook at the upper forward end of said apron portion for attachment to the furnace wall, a portion inclining downward and forward from the rear end of said wings to said 15 furnace wall and forming in connection therewith and said apron an air chamber, and means on said downward and forward inclined portion for detachably engaging therewith and securing thereto a heat insulating block.

12. An apron tuyère unit for attachment to 20 furnace walls comprising an apron portion inclining rearward and downward from the wall, a rib arranged centrally on the underside of said apron portion for reinforcing the same, wings projecting laterally from the opposite sides of the 25 rearward portion of said rib and extending beneath the end of the apron portion to leave open ports therebetween, a hook at the upper forward end of said apron portion for attachment to the furnace wall, a portion inclining downward and 30 forward from the rear end of said wings to said furnace wall and forming in connection therewith and said apron an air chamber, and a channel-shaped downward extension on said downward and forwardly extending portion constituting 35 a means for attaching a heat insulating block thereto.

13. An apron tuyère unit for attachment to furnace walls comprising an apron portion inclining rearward and downward from said wall, 40 a return-portion extending downward and forward to said wall and together with said apron portion forming an air chamber, a tongue projecting from one edge of said apron portion and the opposite edge being provided with a groove 45 whereby a series of said units will form break joints therebetween thereby preventing the sifting of fine fuel into the tuyère to clog the same.

ROYCE L. BEERS.
